UNITED STATES PATENT OFFICE.

LOUIS B. TIM, OF NEW YORK, N. Y.

COLLAR.

982,646.

Specification of Letters Patent. Patented Jan. 24, 1911.

Application filed December 7, 1909. Serial No. 531,754.

To all whom it may concern:

Be it known that I, LOUIS B. TIM, a citizen of the United States, and a resident of the city of New York, borough of Manhattan, in the county and State of New York, have invented a new and Improved Collar, of which the following is a full, clear, and exact description.

This invention relates to certain improvements in that type of turn-down collar in which the rear portion is so constructed as to separate the necktie from the head of the collar button, in order to prevent the necktie from being injured while being moved lengthwise past the collar button in adjusting or tying the tie. Collars have been constructed of this character, in which the neckband portion was formed of two plies separated at the lower edge, and in one of which a buttonhole was formed. Collars have also been made in which a tab has been employed to extend either upwardly or downwardly upon the outer surface of the neckband, or to extend upwardly or downwardly upon the inner surface of the neckband and to carry the buttonhole, in order that the necktie might not engage with the head of the collar button.

In securing a collar to the rear collar button, it is customary, if not necessary, to hold the collar at the back portion thereof, and to reach over the shoulder to the collar button. Thus, the hand is mostly above the collar, and it is very difficult to separate the portion having the button hole from the adjacent portion of the collar, so as to attach this buttonhole portion to the collar button. This is particularly true in that type of collar in which the buttonhole bearing portion and the button-protecting portion are secured together at the upper edge and are free from each other at the lower edge. In collars in which the buttonhole-bearing portion is in the form of a tab secured at only one edge, the tab if it be at all wilted, often will not properly hold the collar, for it is necessary to pull the tie lengthwise through the collar and the tie is of such thickness that it encounters material resistance.

The object of my invention is to so construct and secure the buttonhole-bearing portion, that it may be readily separated from the adjacent portion of the neckband, so as to facilitate the attachment of the buttonhole-bearing portion to the button. I sepa-

rate the two not only at their lower edges, but also along their upper edges, so that the thumb or finger may be extended entirely through the space between the buttonhole-bearing portion and the neckband, and the buttonhole-bearing portion firmly grasped from above to force the button through the buttonhole. Furthermore, by securing the buttonhole-bearing portion at its ends, no amount of lengthwise pulling on the collar can bend or displace the buttonhole-bearing portion any more than if the neckband itself were directly secured to the button.

Reference is to be had to the accompanying drawings, forming a part of this specification, in which similar characters of reference indicate corresponding parts in all the figures, and in which—

Figure 1 is a perspective view of a collar 75 constructed in accordance with my invention; Fig. 2 is a longitudinal horizontal section on the line 2—2 in Fig. 1, through the rear portion of the collar, showing the collar button and necktie in operative position; 80 and Fig. 3 is a section similar to Fig. 2 but showing the buttonhole-bearing portion spaced from the neckband proper and ready to be secured to the collar button.

My improved collar is of the turn-down 85 type, and is constructed with the ordinary neckband or standing portion 10, and the ordinary turn-down portion 11 secured to the neckband along the upper edge of the latter. The neckband portion is provided 90 with the customary buttonholes 12, at the front edge thereof, but there is no rear buttonhole directly in the neckband.

The main feature of my collar is a band or strip 13, secured to the inner surface of 95 the neckband or standing portion at the rear of the latter. This band 13 is of a height considerably less than the height of the neckband, and is secured adjacent the lower portion of the lower half of the neckband. The 100 upper edge of the band 13 is substantially straight, although it may be covered slightly if desired, and the lower edge preferably curves downwardly, so that its center portion extends below the lower edge of the neckband. Thus, by placing the finger between the neckband and the turn-down portion and pulling forwardly, the band or strip may be readily separated from the neckband. This band or strip 13 has a 105 buttonhole 14 intermediate its ends, and the ends of the band are cut on diagonal and up-

wardly-converging lines and secured to the neckband by lines of stitching 15. The buttonhole-bearing portion 13 is thus secured to the neckband along two separate spaced lines upon opposite sides of the buttonhole, so that a longitudinal pulling of the collar will not displace the buttonhole-bearing portion. The collar naturally lies substantially in a curved line, and as the two lines of stitching 15-15 are spaced apart along the necktie, it is evident that the distance along the collar from one line of stitching 15 to the other, will be slightly greater than an air line from one to the other. Thus the buttonhole-bearing portion may be moved outwardly and may be caused to assume an outwardly-curved position, as indicated in Fig. 3, so that there will be a free vertical passage between the neckband and the body portion of the buttonhole-bearing strip or band 13. This permits the thumb or finger to be readily inserted between the neckband and the buttonhole-bearing portion from above, so as to firmly hold the buttonhole-bearing portion between the thumb and finger when it is being secured to the button. This is not possible where the neckband is formed of two plies separated at the lower edge, or where there is a downwardly-extending tab on the neckband, or where the tab extends upwardly from the neckband between the neckband and the turn-down portion. By making the lines of stitching upwardly converging, the buttonhole-bearing portion may be spaced from the collar a greater distance at its lower edge than at its upper edge, and may be more easily secured to the button. Furthermore, the buttonhole-bearing portion may be more easily

separated from the neckband, as it is the lower edge of the buttonhole-bearing portion which extends below the neckband and constitutes a tab for use in pulling the buttonhole-bearing portion outwardly.

Having thus described my invention, I claim as new and desire to secure by Letters Patent:

1. A collar having a neckband and a turn-down portion secured to the top edge of said neckband, and provided with a strip extending along the inner surface of the neckband portion at the rear, the ends of said strip being stitched to the collar along upwardly converging lines, and the upper and lower edges of the strip being free and unattached to the neckband, the lower edge of the strip being downwardly curved to extend below the lower edge of the collar, and the strip having a buttonhole intermediate its edges.

2. A turn-down collar having an outer or turned down portion and a neck-band portion and provided with a band intermediate the ends of the neck-band portion upon the inner surface thereof, said band having its outer ends joined to said neck-band portion and having its upper and lower edges free therefrom, said band having a buttonhole intermediate its ends and having a portion of its lower edge extending below the lower edge of the adjacent neck-band portion.

In testimony whereof I have signed my name to this specification in the presence of two subscribing witnesses.

LOUIS B. TIM.
